UNITED STATES PATENT OFFICE.

GEORGE H. CLEVELAND, OF WACO, TEXAS.

SCRIP-HOLDER.

1,103,739.

Specification of Letters Patent. Patented July 14, 1914.

Application filed July 18, 1913. Serial No. 779,841.

To all whom it may concern:

Be it known that I, GEORGE H. CLEVELAND, a citizen of the United States, residing at Waco, in the county of McLennan and 5 State of Texas, have invented new and useful Improvements in Scrip-Holders, of which the following is a specification.

The invention relates to a scrip holder, designed particularly for housing in a conveniently accessible manner the usual railroad scrip.

The main object of the present invention is the provision of a holder arranged within a book cover and constructed to contain the 15 scrip sheet *per se*, or the scrip sheet and cover therefor, the parts being constructed to insure a proper delivery of the scrip from the superimposed holes thereof and the arrangement of the projected strip for convenient coöperation with the cutter, whereby 20 any desired portion of said strip may be severed.

The invention in its preferred form of details will be described in the following specification, reference being had particularly to the accompanying drawings, in which:—

Figure 1 is a perspective view with the outer or book cover open. Fig. 2 is a rear plan with the book cover open. Fig. 3 is a 30 longitudinal vertical section through the holder proper. Fig. 4 is a transverse section on line 4—4 of Fig. 3. Fig. 5 is a transverse section on line 5—5 of Fig. 3. Fig. 6 is a broken perspective of the holder proper 35 showing the auxiliary guard plate partially in place to illustrate its application and use.

With particular reference to the accompanying drawings, the improved holder proper comprises a metallic plate 1 having 40 the side edges thereof bent to provide overlying rectangular flanges 2, said flanges being rectangular in that their sides are at right angles to the plate and their upper free edges overhand the plate in spaced 45 parallel relation thereto. The flanges thus form guides for the reception of the scrip as will presently appear. The lower edge of the plate is free of projection to provide an entrance opening for the scrip, while the 50 upper edge has a rounded or rolled flange extension 3 over which the scrip is drawn, the upper plane of said projection being somewhat below the flanges 2 in order to permit the passage of the strip.

55 Secured to the plate 1 immediately adjacent the upper end thereof is a spring strip 4,

which extends transversely of the plate and is in bowed form serving to exert an upward pressure upon the scrip strip and prevent over-running of the same when withdrawing it from the holder. A bearing plate 5 is slidably mounted on the plate 1 preferably having downturned edge flanges 6 which fit within the guides, the plate occupying a position above the strip serving as a bearing 60 plate between which and the spring the strip passes. The plate 1 is further provided with an abutment 7 which extends throughout the full width of the plate in a position practically coincident with the relatively 65 lower edge of the bearing plate. The abutment is of slightly less height than the depth of the guides and serves to limit the upper position of the superimposed folds of the scrip strip, so as to insure the uppermost 70 strip or leaf of said folds being singly withdrawn from the pile, the abutment preventing such folds below the uppermost from being withdrawn from the holder, as will be 75 obvious.

Secured to one side of the holder proper and forming in effect a fixed part thereof, is a rod 8, the connection between the holder and rod being preferably formed by cutting the upper and lower ends of the adjacent 80 guide and bending the material thus formed about the rod, as at 9. The connection of the rod to the holder is such that the rod is disposed in spaced parallel relation to the adjacent guide and approximately centrally 85 of the height thereof, and slidably mounted upon the rod is what I term a cutter 10 comprising a strip practically coincident in length with the width of the plate 1 and having one terminal thereof coiled to provide 90 a sleeve bearing 11, which loosely encircles the rod 8. By this arrangement the cutter is adapted to contact throughout this length with the rear of the plate 1 and is manually adjustable to any desired position 95 longitudinally of said plate through the sliding connection of the cutter on the rod. Furthermore by the position of the rod mid-distant the thickness of the adjacent guide flange and the relatively offset relation of 100 the sleeve 11 to the cutter, there is no projection of the parts beyond either surface of the holder proper. The rear surface of the plate 1, or that portion which the cutter overlies has a marginal line of indicating 105 numerals 12 progressing in multiples in accordance with the successive amounts on the 110

scrip, the numerals preferably extending from the lower edge of the plate toward the upper edge. In the present instance, these numerals are shown as successively increasing by 5, and each numeral is arranged in the space outlined by a transverse line, with the distance between the respective lines corresponding to the similar distance between the separable sections of the scrip.

10 The holder proper is secured in what I term a book cover 13 comprising the usual cover sections in which the holder is hingedly or movably mounted at 14 in any approved or appropriate manner. The inner 15 surface of the back section of the book cover is provided with spaced straps or pockets 15, for the purpose which will presently appear.

In connection with the holder proper I use what I term a guard plate 16 which is 20 in use when the ordinary scrip cover is not applied with the scrip strip to the holder, this guard plate comprising a plate section 17 corresponding in width to that of the plate 1 and in length to the distance from 25 the lower edge of the plate 1 to the abutment 7. The guard plate is formed with a right angled edge flange 18 coextensive with the sides and lower edge thereof, said guard plate being inserted within the guide flanges 30 so that the plate proper bridges the space between the upper portions of said guide flanges and the depending flanges 18 rest on the plate 1.

In the use of the device where it is 35 signed to use the scrip strip 19 within the usual cover 20 provided therewith, the guard plate is omitted and the cover 20 with the contained scrip strip is inserted in the guard flanges to overlie the plate 1, with 40 the cover 20 so folded that the identification portion thereof is exposed for its usual purpose. The terminal of the strip 19 is passed beyond the upper edge of the cover 20, over the abutment 7 and between the 45 spring 4 and plate 5, being then passed over the rounded upper end of the plate 1 and lengthwise the back of the plate, where any desired portion may be severed by the obvious use of the cutter, the particular portion 50 to be severed being determined in the usual manner by the inscribed figures 12 on the back plate. When the holder is to be used simply for the scrip strip without the cover 20 in position thereon the strip 19 is 55 inserted in place and the guard plate then applied to the same, protecting the strip and preventing the folds thereof within the holder from becoming displaced, the abutment 7 in both instances serving to prevent 60 more than the uppermost section of the strip passing from the holder in withdrawing operation.

When the guard plate is in use, the cover 20 of the scrip strip is inserted in the pockets 65 with the identification surface thereof ex-

posed, so that it is readily accessible for inspection.

By the peculiar arrangement of the parts described it will be obvious that the completed article when in closed position forms 70 a compact receptacle of a decidedly ornamental character, which may be readily and conveniently carried in the pocket and which by the peculiar construction of the parts permits the convenient withdrawal of 75 that portion of the scrip strip which it is designed to sever, with the remainder of the strip completely housed and protected within the structure.

What is claimed is:—

1. A scrip holder comprising a main plate formed with guide flanges on its edges, an abutment transverse the plate near one end thereof, said guide flanges and abutment serving to retain the scrip in folded form 80 within the holder, and strip friction means carried by the plate beyond the abutment.

2. A scrip holder comprising a main plate formed with guide flanges on its edges, an abutment transverse the plate near one end 90 thereof, strip friction means carried by the plate beyond the abutment, and a book cover in which the holder is movably connected.

3. A scrip holder comprising a main plate formed with guide flanges on its edges, an 95 abutment transverse the plate near one end thereof, strip friction means carried by the plate beyond the abutment, a book cover in which the holder is movably connected, and spaced receiving pockets formed on the rear 100 section of the book cover.

4. A scrip holder comprising a main plate formed with guide flanges on its edges, an abutment transverse the plate near one end 105 thereof, strip friction means carried by the plate beyond the abutment, a rod secured to the plate, and a cutter slidably mounted on the rod.

5. A scrip holder comprising a main plate formed with guide flanges on its edges, an 110 abutment transverse the plate near one end thereof, strip friction means carried by the plate beyond the abutment, a rod secured to the plate within the plane of the opposing surface of the plate, and guide flanges, and 115 a cutter slidably mounted on the rod.

6. A scrip holder comprising a main plate formed with guide flanges on its edges, an abutment transverse the plate near one end 120 thereof, strip friction means carried by the plate beyond the abutment, a rod secured to the plate within the plane of the opposing surface of the plate and guide flanges, a 125 cutter slidably mounted on the rod, and overlying the rear of the plate, said rear portion of the plate having a marginal line of indicating numerals.

7. A scrip holder comprising a main plate formed with guide flanges on its edges, an abutment transverse the plate near one end 130

thereof, strip friction means carried by the plate beyond the abutment, and a guard plate coöperating with the guide flanges and forming with the main plate a housing for 5 the scrip strip.

8. A scrip holder comprising a main plate formed with guide flanges on its edges, an abutment transverse the plate near one end thereof, strip friction means carried by the 10 plate beyond the abutment, and a guard plate coöperating with the guide flanges and forming with the main plate a housing

for the scrip strip, said guard plate having a width coextensive with the width of the main plate and the length equal to the 15 length of the main plate from the lower edge to the abutment.

In testimony whereof I affix my signature in presence of two witnesses.

GEORGE H. CLEVELAND.
